UNITED STATES PATENT OFFICE.

FREDERICK E. KOHLER, OF CANTON, OHIO.

DESIGN FOR A LAWN-RAKE.

SPECIFICATION forming part of Design No. 22,605, dated July 11, 1893.

Application filed April 13, 1893. Serial No. 470,254. Term of patent 7 years.

To all whom it may concern:

Be it known that I, FREDERICK E. KOHLER, a citizen of the United States, and a resident of Canton, county of Stark, State of Ohio, have 5 invented and produced a new and original Design for a Lawn-Rake, of which the following is a full, clear, and exact description, reference being had to the accompanying drawings, making part of this specification.

10 This design relates to garden and lawn rakes, and its leading feature is a plate which extends from end to end of the rake beam, and projects inward and upward and has its end cut on an incline whereby a neat and ornamental appearance is given to the implement.

15 In the accompanying drawings Figure 1 represents a perspective view of the garden rake showing my design. Fig. 2 is a side view.

20 In the said drawing, letter A designates the

handle of the rake, C the rake bar, and D the teeth. At the top of the rake bar is a plate E, extending from end to end thereof, and having its inner edge projecting inwardly and bent upwardly at an angle as shown and the ends cut on a bevel as shown at F. B designates the handle socket.

A rake as above described and shown is very ornamental in appearance and pleasing to the eye.

30 What I claim is—

The design for a garden rake herein shown and described.

In testimony whereof I have hereunto set my hand this 29th day of March, A. D. 1893. 35

FREDERICK E. KOHLER.
